UNITED STATES PATENT OFFICE

2,424,251

SELF-ADJUSTING GARTER

Naomi Morton, New York, N. Y.

Application June 14, 1944, Serial No. 540,207

6 Claims. (Cl. 2-315)

1

This invention relates to new and useful improvements in self-adjusting garters.

The garters generally worn by women are unsatisfactory in that there is no arrangement for shifting the support of the hose as the wearer stands up and sits down. For this reason there is a tendency for the hose to be pulled and become shifted and distorted over a short period of time.

This invention proposes a self-adjusting garter which is characterized by a cloth strip for attachment upon the bottom edge portion of some undergarment, and supporting a rigid link. It is proposed to engage a strap through this link and to provide this strap with garter gripping members for engaging the top of the hose. With this arrangement when a person sits down and stands up there will merely be a relative shifting of the rigid link in relation to the strip and this will better transfer undesirable stresses to the hose.

More specifically, the invention proposes certain improvements in a self-adjusting garter as briefly outlined. An improvement is proposed in the way in which the rigid link is supported. Additional improvements are proposed in the construction and relationship between the rigid link and strap which is provided with the stocking gripping members.

Another object of the invention is the construction of an article as mentioned which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is an illustration of a self-adjusting garter constructed in accordance with this invention and shown in use.

Fig. 2 is an enlarged vertical sectional view taken on the line 2-2 of Fig. 1.

Fig. 3 is another illustration similar to Fig. 1 but disclosing a modified form of the self-adjusting garter.

Fig. 4 is a fragmentary enlarged vertical sectional view taken on the line 4-4 of Fig. 3.

Fig. 5 is an enlarged fragmentary perspective view of the rigid link arrangement shown in Fig. 3.

Fig. 6 is a perspective view of the cloth strip used for supporting the rigid link.

2

Fig. 7 is a fragmentary enlarged detailed elevational view of a portion of the strap of the garter.

The self-adjusting garter, in accordance with this invention, is used in combination with an undergarment 10 having a bottom edge portion 11 located slightly above the top of one's stockings 12. Each garter includes a cloth strip 14 bent upon itself to form a loop (see Fig. 2). The ends of the cloth strip 14 are attached to said bottom edge portion 11 so that said loop extends downwardly.

A rigid link 15 engages through the loop of the cloth strip 14. A strap 16 engages through the link 15. Conventional stocking gripping members 17 are mounted upon the ends of the strap 16. In the particular design of the self-adjusting garter disclosed, the rigid link 15 is in the nature of a ring. The cloth strip 14 preferably includes elastic threads so as to have elastic qualities.

The self-adjusting garter is used by engaging the stocking gripping members 17 to the top of one's stocking, as illustrated in Fig. 1. These gripping members 17 should be so positioned that the section of the strap 16 to the back of the rigid link 15 is shorter than the section of the strap 16 to the front of the rigid link 15. The parts are so illustrated in Fig. 1. With this arrangement the hose may be supported in the best possible way. Then the rigid link 15 will move the least amount along the strap 16 when a person sits down and stands up. No twisting tendencies will be communicated to the stocking 12.

In Figs. 3-7 inclusive a modified form of the invention is disclosed which distinguishes from the prior form in several respects. In this form of the invention the cloth strip 14' is provided with several openings 20 in its end portions. The bottom edge portion 11' of the garment 10 is formed with a series of complementary openings 21 spaced to align with the openings 20. A lace 22 is engaged through the openings 20 and through certain of the openings 21 for holding the strip 14' in selected positions along the bottom edge portion 11' of the undergarment 10. A cover strip 23 is attached upon the inner face of the undergarment 10 and extends along the bottom edge portion 11' and is secured in position by stitches 24 along the top and ends so as to form a pocket 25 into which the upper end of the strip 14' engages.

The strap 16' is formed with a series of openings 26 along its length through which a cord 55 or lace 27 is laced to provide a plurality of loops.

A rigid link 15' engages through the loop of the strip 14'. This rigid link 15' has parallel straight top and bottom sides connected by curved ends. A tube 28 is mounted upon the bottom side of the rigid link 15'. When the strap 16' is engaged over the tube 28, one loop of the lace 27 is engaged beneath the tube 28, as illustrated for example in Fig. 4, so that shifting of the strap 16' will be limited to the distance defined by said loop of the lace 27. In this way the strap 16' will be limited to shift through a preselected amount which is sufficient to prevent undue stresses from being communicated to the stocking, provided that the strip 14' is at a proper location along the bottom portion 11' of the garment 10. It is for this reason that the strip 14' is adjustably mounted to be shifted to selected positions along the bottom edge portion 11'.

In other respects this form of the invention is similar to that previously shown and like reference numerals identify like parts in each of the several views.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In combination with an undergarment having a bottom edge portion slightly above the top of one's stocking, a cloth strip bent upon itself to form a loop and attached at its ends upon and depending from said bottom edge portion, a rigid link engaging through the bottom of said loop, a strap engaging through said link, stocking gripping members on the ends of said strap, and said cloth strip being adjustably attached on said bottom edge portion, said strap being provided with a cord laced through spaced openings thereof, forming several loop portions for engaging beneath said link limiting shifting of the strap through the link.

2. In combination with an undergarment having a bottom edge portion slightly above the top of one's stocking, a cloth strip bent upon itself to form a loop and attached at its ends upon and depending from said bottom edge portion, a rigid link engaging through the bottom of said loop, a strap engaging through said link, stocking gripping members on the ends of said strap, said strap being provided with a cord laced through spaced openings thereof, forming several loop portions for engaging beneath said link for limiting shifting of the strap through the link, where said above mentioned cloth strip has openings, said bottom edge portion has a series of complementary openings, and there is a lace engaged through these openings for holding said cloth strip in selected positions.

3. In combination with an undergarment having a bottom edge portion slightly above the top of one's stocking, a cloth strip bent upon itself to form a loop and attached at its ends upon

and depending from said bottom edge, a rigid link engaging through the bottom of said loop, a strap engaging through said link, stocking gripping members on the ends of said strap, and means for limiting shifting of said strap relative to said loop, comprising a lace looped between the two parts of said strap on either side of said link fitting into openings in said strap and being adjustable in length by selectively knotting the lace ends.

4. In combination with an undergarment having a bottom edge portion slightly above the top of one's stocking, a cloth strip bent upon itself to form a loop and attached at its ends upon and depending from said bottom edge, a rigid link engaging through the bottom of said loop, a strap engaging through said link, stocking gripping members on the ends of said strap, and means for limiting shifting of said strap relative to said loop, comprising a cord laced through spaced openings formed in said strap forming several loop portions selectively engageable beneath said link.

5. In combination with an undergarment having a bottom edge portion including a pocket reinforcement slightly above the top of one's stocking, a cloth strip bent upon itself to form a loop for having its ends attached to said bottom edge to depend therefrom, a rigid link engaging through the bottom of said loop, a strap engaging through said link, stocking gripping members on the ends of said strap, and means for adjustably attaching the ends of said strip to said bottom edge portions at the side of said pocket reinforcement.

6. In combination with an undergarment having a bottom edge portion including a pocket reinforcement slightly above the top of one's stocking, a cloth strip bent upon itself to form a loop for having its ends attached to said bottom edge to depend therefrom, a rigid link engaging through the bottom of said loop, a strap engaging through said link, stocking gripping members on the ends of said strap, and means for adjustably attaching the ends of said strip to said bottom edge portions at the side of said pocket reinforcement, said ends being formed with spaced openings selectively alignable with a series of similarly spaced openings formed in said bottom edge portion, said means, comprising a lace engageable through the aligned openings of said strip and bottom edge portion.
